UNITED STATES PATENT OFFICE

164,371

COMBINATION AUTOMOBILE AND
AIRPLANE

Edward Carl La Voque, Seattle, Wash.

Application January 23, 1951, Serial No. 13,927

Term of patent 14 years

(Cl. D71—1)

To all whom it may concern:

Be it known that I, Edward C. La Voque, a citizen of the United States of America, residing at Seattle, in the county of King and State of Washington, have invented a new, original, and ornamental Design for a Combination Automobile and Airplane, of which the following is a specification, reference being had to the accompanying drawing, forming a part hereof.

Figure 1 is a perspective view of the combination automobile and airplane conditioned for flying, illustrating the new design.

Figure 2 is a plan view of the vehicle.

Figure 3 is a side elevation view thereof.

Figure 4 is a front elevation view of the same, with outer portions of the wings broken away for convenience in illustration.

Figure 5 is a perspective view of the vehicle from the rear.

Figure 6 is a perspective view similar to Figure 4, but with the wings folded in condition for road travel.

I claim:

The ornamental design for a combination automobile and airplane, as shown.

EDWARD CARL LA VOQUE.
